[57] CLAIM

The ornamental design for a bottle with cap and sleeve, as shown and described.

DESCRIPTION

FIG. 1 is a perspective view of a bottle with cap and sleeve, embodying our new design;

FIG. 2 is a side elevational view thereof, the other side elevational view thereof being the same;

FIG. 3 is a front elevational view thereof with the back elevational view thereof being the same;

FIG. 4 is a bottom view thereof; and,

FIG. 5 is a top view thereof.
